WASHER GAIN FOR POLE CROSSARM

William A. Horning, 4011 Wauna Vista Dr.,
Vancouver, Wash.

Filed June 22, 1964, Ser. No. 80,503

Term of patent 14 years

(Cl. D54—1)

FIG. 1 is a front view of a washer gain for pole cross-arm in accordance with my new design;

FIG. 2 is a side view;

FIG. 3 is a top view;

FIG. 4 is a back view.

FIG. 5 is a section view taken on the line 5—5 of FIG. 4, on a slightly reduced scale.

I claim:

The ornamental design for a washer gain for pole cross-arm, as shown.
